UNITED STATES PATENT OFFICE.

CHARLES SCHULTZ, OF CHICAGO, ILLINOIS.

DESIGN FOR A QUILTING FABRIC.

SPECIFICATION forming part of Design No. 20,019, dated July 15, 1890.

Application filed May 29, 1890. Serial No. 353,670. Term of patent 3½ years.

To all whom it may concern:

Be it known that I, CHARLES SCHULTZ, a citizen of the United States, residing at Chicago, in the county of Cook and State of Illinois, have invented and produced a new and original Design for Quilting Fabric, of which the following is a specification, reference being had to the accompanying drawing, forming a part thereof.

- 10 The drawing is a diagrammatic plan.
My design consists of a quilted pattern representing a series of lines traversing the fabric diagonally in one direction and another series of lines diagonally traversing the fabric 15 in a contrary direction, the two series of lines crossing each other at right angles, thus dividing the pattern into compartments.

To render the fabric more beautiful, my de-

sign further consists of quilted figures representing stars located centrally in the square 20 or lozenge shaped compartments aforesaid, and suspended from one of the angles or corners of such compartments.

What I claim is—

The design for a pattern for quilting fabric 25 herein shown and described, and consisting of quilted figures representing angular compartments, and suspended stars located centrally in said compartments.

In testimony whereof I sign this specification, in the presence of two witnesses, this 14th day of May, 1890.

CHARLES SCHULTZ.
